IMPRESSED-PICTURE MEDIUM

Max Finke, Emmendingen, Germany

Application February 8, 1937, Serial No. 124,594
In Germany August 13, 1936

5 Claims. (Cl. 154—46)

It is known, to make impressed-picture medium from thin metal sheet, especially from aluminium foil. For the production of such picture medium one employs thin metal sheets, especially aluminium foils, pasted on paper of various thickness. For production of light effects either the whole surface of the metal foil to be impressed may be provided with engraving or fine impressions (markings), or only selected parts of the said surface, that is to say opposite the places which in the finished pressed figure are to stand out especially bright. The pressing of such foils with positive and negative dies presents no difficulty, and the pressure necessary to effect the relief stamping in such a case can be produced without difficulty.

But if the pressing die, by means of which selected parts, or the whole of the surface of the metal foil to be pressed which is mounted on a backing, are to be impressed is made of yielding material, it is necessary that the foil to be impressed, placed on a support, be likewise soft and the pressure be lightly yielding.

To this end the thin metal foil has been mounted on the paper by means of a soft plastic layer or bed. This plastic interposed layer, serving as an adhesive, has not only performed the function of binding the metal, especially aluminium foil to the paper, but also at the same time of producing the presumption that by means of a yielding die the desired impression can be pressed in the foil.

It has appeared that this interposed binding layer, which at the same time constitutes a plastic mass to receive the impression does not, in consequence of the uneven contour of the paper surface and also by reason of the capacity for absorption of the latter, work well in uniform thicknesses, which is absolutely essential especially in the production of complete thin impressions. In both impression and pressure processes a large percentage of waste must always be allowed for. In addition there is the possibility that during storage the layer interposed between the paper and the metal foil may, on the paper side, penetrate into the paper fibres. Moreover, the interposed layer loses, in course of time, its plasticity.

In the drawing, the sole figure represents a cross-sectional view of the material.

The subject of the present invention is an impressed-picture medium in which a thin metal, especially aluminium foil 5 may be employed which by means of a plastic adhesive is pasted to a base with, however, the distinction that as a

base a layer is employed which has no fibrosity. For this there is best adopted a preferably somewhat thicker metal—preferably aluminium foil 3. This produces, with the aluminium foil to carry the picture and impression, a second foil, which 5 is adhesively secured to the first by means of the plastic interposed layer 4.

In order to obtain a durable or more resistant product, the thin metal, especially aluminium foil, which is to be impressed and pressed, may be 10 provided with such a metal foil 3 which is backed with paper 1 by means of a normally non-plastic adhesive 2. Thus a product is obtained which consists of paper 1, plus a binding layer 2, plus metal foil 3, plus a plastic interposed layer 4, and 15 lastly the picture and engraving carrying thin metal foil 5.

The plastic interposed layer, lying between the two metal foils, and binding the same together, can either remain permanently plastic or can 20 obtain this characteristic by heat treatment during the process of impressing (pressing).

In the latter case there can be produced and impressed (pressed) picture, in which a much better resistance to damage is offered than in a 25 picture produced by the first method, since the interposed layer, which becomes plastic in the heat, as a result of subsequent cooling stiffens and hardens.

Obviously one can choose as backing material 30 for foils to be impressed with colours, such foundations as do not allow the plastic interposed layers to be absorbed or evaporated, as for instance a varnished paper, or a cellulose material either mounted on paper or in the form of 35 sheets.

I claim:

1. A backed metal foil for receiving ornamental designs impressed flat in the surface, having a further metal foil interposed between the metal 40 foil and the paper layer serving as base for the backing, and a plastic adhesive layer between the metal foils as well as an adhesive layer between the intermediate foil and the paper layer.

2. A backed aluminum foil for receiving ornamental designs flat impressed in the surface, having a further metal foil interposed between the metal foil and the paper layer serving as base for the backing, and a plastic adhesive layer between the metal foils as well as an adhesive layer 50 between the intermediate foil and the paper layer.

3. A backed metal foil for receiving ornamental designs flat impressed in the surface, having an aluminum foil interposed between the metal foil and the paper layer serving as base for the 55

backing, and a plastic adhesive layer between the metal foils as well as an adhesive layer between the intermediate foil and the paper layer.

4. A backed aluminum foil for receiving ornamental designs flat impressed in the surface, having an aluminum foil interposed between the metal foil and the paper layer serving as base for the backing, and a plastic adhesive layer between the metal foils as well as an adhesive layer between the intermediate foil and the paper layer.

5. A backed metal foil for receiving ornamental designs flat impressed in the surface, having a further metal foil interposed between the metal foil and the paper layer serving as base for the backing, and an adhesive layer between the metal foils which is plastic in the heat and hard at normal temperature, as well as an adhesive layer between the intermediate foil and the paper layer.
